(57) **CLAIM**

The ornamental design for a pet feeder, as shown and described.

DESCRIPTION

FIG. 1 is a perspective view of a pet feeder of the present design showing the front, top and first side portions of the pet feeder in a closed configuration;

FIG. 2 a perspective view of the pet feeder of the present design showing the back, top, and second side portions of the pet feeder in the closed configuration;

FIG. 3 is a top view of the pet feeder of the present design showing the top portion of the pet feeder in the closed configuration;

FIG. 4 is a front view of the pet feeder of the present design showing the front portion of the pet feeder in the closed configuration;

FIG. 5 is a side view of the pet feeder of the present design showing the second side portion of the pet feeder in the closed configuration;

FIG. 6 is a bottom view of the pet feeder of the present design showing the bottom portion of the pet feeder; and

FIG. 7 is a front perspective view of the pet feeder of the present design in which the cover is shown in an open position;

FIG. 8 is a side view of the pet feeder of the present design showing the first side portion of the pet feeder in the closed configuration;

FIG. 9 is a back view of the pet feeder of the present design showing the back portion of the pet feeder in the closed configuration; and,

FIG. 10 is a perspective view of the pet feeder of the present design showing the bottom, back, and first side portions of the pet feeder in the closed configuration.

The broken lines in the drawings depict unclaimed subject matter only and form no part of the claimed design.

1 Claim, 10 Drawing Sheets
